UNITED STATES PATENT OFFICE.

ALPHONSE F. PIEPER, OF ROCHESTER, NEW YORK.

DESIGN FOR A UNIVERSAL JOINT.

Application filed January 26, 1923. Serial No. 5,006. Term of patent 14 years.

To all whom it may concern:

Be it known that I, ALPHONSE F. PIEPER, a citizen of the United States, residing at Rochester, in the county of Monroe and State of New York, have invented a new, original, and ornamental Design for Universal Joints, of which the following is a specification, reference being had to the accompanying drawings, forming part thereof.

In the drawings:

Figure 1 is a side view of a universal joint showing my new design.

Figure 2 is a view similar to Figure 1 but as seen from the right in the latter.

I claim:

The ornamental design for a universal joint, as shown.

ALPHONSE F. PIEPER.
